Inventor:

Eugene Meyer,
By his Attorney, Clark Knatz

UNITED STATES PATENT OFFICE.

EUGENE MEYER, OF NEW YORK, N. Y.

RESONANCE HORN

Application filed August 14, 1922. Serial No. 581,762.

to all whom it may concern:

Be it known that I, EUGENE MEYER, a citizen of the United States, and a resident of the borough of Manhattan, city, county, and State of New York, have invented certain new and useful Improvements in Resonance Horns, of which the following is a specification.

My invention relates to horns used either for receiving or transmitting sound vibrations, and consists essentially in the combination and incorporation, with such a horn, of one or more, preferably a plurality, of sound amplifying resonant tubes, substantially in the manner and for the purposes herein fully set forth and described and claimed specifically.

In the accompanying drawings I exemplify a practical embodiment of the essential features of my invention in conjunction with a conoidal horn of well known configuration, and show a plurality of resonant tubes positioned internally and radially around the inner concavo-conoidal surface of said horn, with the understanding that I do not limit myself to this identical form and construction of parts, since modifications may be resorted to in arrangement, and in minor details, with like result, and without deviating from the spirit and intent of my invention in this respect.

With this understanding,

Fig. 1, is a front end elevation of my improved resonance horn;

Fig. 2, is a longitudinal section thereof taken upon plane of line 2—2, Fig. 1;

Fig. 3, is a diagrammatic representation of the inner surface of the horn, the latter being presumed to be split longitudinally and spread out flat;

Fig. 4, is a diagrammatic elevation of the horn, showing its use as a means of making sound records;

Fig. 5, is a similar view illustrating its use in conjunction with phonographic sound box;

Fig. 6, is a similar view showing the horn adapted for use as a trumpet;

Fig. 7, is a detail view of an elbow suitable for use as a coupling between horn and phonograph sound box.

The function of resonance tubes in amplifying sound vibrations is well known, and I do not claim anything original in this respect, the novelty in the present case con-

sisting in permanently equipping a horn of the character designated with one or more such intensifying mediums, preferably a plurality of such tubes, representing an octave or more, incorporated and positioned rigidly in the interior of the horn H, and radially convergent, as illustrated particularly in Fig. 3, of the drawings, with their open extremities toward the apex end h, of the horn.

Thus in Figs. 1, 2, and 3 of the drawings I show a series of resonant tubes r, r, representing thirteen notes of the musical scale, eight natural from E to E inclusive, and the five intermediate notes D#, C#, A#, G#, and F#, although I do not limit myself in this particular, as any number, and combination and arrangement of resonant tubes, may be resorted to in adapting the device to various purposes and uses.

Preferably the series of resonant tubes r, r, are arranged radially as shown, and as related to the apex of the horn; and may be affixed to the latter by glue, cement, or any other positive means.

S is a sound conveying tube or conduit, the main portion of which is positioned in alignment with the longitudinal axis of the horn, said sound conduit S, being formed with a lateral extension s, protuberant through the side of the horn.

This sound conveying conduit S, is for the purpose of transmitting sound vibrations in either directions. Thus, as shown in Fig. 4, the extraneous extension s, thereof may be attached to a record-producing device D, of well known construction, for making a record on the usual wax receiving disc d; or the outer end of the extension s, may be placed to the ear of a person for the purpose of listening to sound vibrations received into the mouth of the horn, and modified and amplified by the resonator tubes r. Or, a phonographic sound box B, may be attached to the end of the horn, as indicated in Fig. 5, to transmit the vibrations imparted by the phonographic record P, through the horn in intensified volume, a tubular coupling elbow e, such as indicated in Fig. 7, being used to connect the box B, and the otherwise open apex end of the horn.

Or the apex of the horn H, may be provided with a mouth piece m, as indicated in Fig. 6, and the horn used as a speaking or singing trumpet if so desired. In fact

my sound amplifying horn may be adapted to many and various uses without departing from the spirit and intent of my invention.

What I claim as my invention and desire to secure by Letters Patent is,

1. The combination with a conoidal horn of the character designated, of a plurality of resonant tubes, each for a definite note of the chromatic scale, positioned convergently therein, said tubes all having open ends facing the producer from the inside of the horn, the other ends being closed, substantially in the manner and for the purpose set forth.
2. A conoidal horn of the character designated, having a plurality of resonant tubes, each for a definite note of the chromatic scale, said tubes being open at one end and closed at the other, and positioned in the horn radially convergent thereto with their open extremities toward the apex of the horn, substantially in the manner and for the purpose set forth.

EUGENE MEYER.
